UNITED STATES PATENT OFFICE.

JOE E. COURTNEY, OF PLAINVIEW, TEXAS.

RAILWAY HIGHWAY STOP.

Application filed April 26, 1923. Serial No. 634,802.

To all whom it may concern:

Be it known that I, JOE E. COURTNEY, a citizen of the United States, residing at Plainview, in the county of Hale and State 5 of Texas, have invented a new and useful Railway Highway Stop, of which the following is a specification.

This invention relates to railway crossing gates, and more particularly to a crossing 10 gate of the automatic type, the operating means associated with the gate being train controlled to actuate the gate at a point remote from the gate proper.

The primary object of the invention is to 15 provide a gate operating means which will be actuated by the movement of a train to close the gate when a train is approaching a crossing, the operating means being actuated to open the gate when the train has 20 passed the crossing.

Another object of the invention is the provision of means for locking the gate in its open or closed position, to insure against wind moving the gate from its open or closed 25 position.

With the foregoing and other objects in view which will appear as the description proceeds, the invention resides in the combination and arrangement of parts and in the 30 details of construction hereinafter described and claimed, it being understood that changes in the precise embodiment of the invention herein disclosed, may be made within the scope of what is claimed, without 35 departing from the spirit of the invention.

Referring to the drawings:

Figure 1 is a plan view of a gate and operating means constructed in accordance with the invention and disclosing the same 40 in its closed position, over a highway at a railway crossing.

Figure 2 is an enlarged elevational view of the gate and its supporting post.

Figure 3 is a longitudinal sectional view 45 through the hollow supporting post.

Figure 4 is a sectional view on line 4-4 of Figure 3.

Figure 5 is a sectional view on line 5-5 of Figure 3.

50 Figure 6 is a sectional view on line 6-6 of Figure 4.

Figure 7 is a diagrammatical view of the gears employed for operating the gate.

Figure 8 is a sectional detail view of the 55 pawl and ratchet construction.

Figure 9 is an enlarged sectional detail

view disclosing the means for controlling the operating mechanism of the gate.

Referring to the drawings in detail, the supporting post for the gate is indicated at 5, the same being hollow, the upper end thereof being closed by means of the cap 6 formed with a central opening to accommodate the shaft 7 on which the gate proper 7' is mounted to swing in a horizontal plane. 60 This post 5 is positioned at a point adjacent to one side of a highway and in proximity to a railway track to swing across the highway and prevent persons from passing onto the tracks when a train is approaching the 65 highway.

The means for operating the gate embodies an operating rod 8 that moves through suitable bearings formed in the braces 9 and 10 which have their ends secured to the inner wall of the post 5 as clearly shown by Figure 3 of the drawings. 70 This operating rod 8 is formed with a bore extending from the free end thereof and terminating at a point substantially intermediate the end of the rod, which bore is designed to accommodate the rod 11 to which is secured a cross arm 12 that carries 75 pawls 13.

Cooperating with the pawls 13 are shoulders 14 formed at the inner ends of the inclined surfaces 15 formed integral with the rod 8, the pawls being designed to ride over the inclined surfaces 15 and engage the shoulders 14 to connect the rods 8 and 11. 80

The brace 10 is formed with cams 16 lying in the paths of travel of the pawls 13 when the pawls move to the limits of their inward movements with the result that the pawls are released from the shoulders for purposes to be hereinafter more fully described. The rod 11 is relatively long and is supported in bearings 17 of the braces 18 and 19, the brace 19 being also provided with a suitable bearing to support the 100 shaft 7.

Brackets 20 are also secured to the inner wall of the post 5 and support the bearing 21 on the inner ends thereof, which bearing 21 also holds the segmental gears 22 and 23, 105 in spaced relation with each other, the segmental gears 22 and 23 being secured to the shaft 7 as by means of the bolts 24.

Secured to the shaft 7 to move therewith, is a segment indicated at 25 which is formed with depressions 26 and 27 arranged adjacent to the side edges of the sections, the de-

pressions being designed to receive the plunger 28 in one end of the rod 11, whereby the shaft is locked in predetermined positions to prevent the same from being rotated by means other than the actuating mechanism.

Associated with the segmental gears 22 and 23 is a ratchet wheel 29 which has a mutilated gear 30 formed on one surface thereof to contact with the teeth of the segmental gears to rotate the same and cause a relative movement of the shaft supporting the gears 22 and 23.

The inner surface of the ratchet wheel 29 is formed with teeth 31 that cooperate with the pivoted pawls 32 carried by the support 33 keyed or otherwise secured to shaft 34, which shaft has one end thereof mounted in the bearings 35 secured to the inner wall of the hollow post 5.

Coiled springs 36 are mounted in suitable openings formed in the support 33, the free ends of the springs contacting with the inner edges of the pawls 32 to normally urge the pawls into engagement with the teeth 31 of the ratchet wheel. Thus it will be seen that as the ratchet wheel moves in one direction, the support and pawls are carried with the ratchet wheel, but upon reverse movement of the ratchet wheel, the teeth 31 ride over the pawls to the end that the ratchet wheel moves independently of the support and pawls.

As shown by Figure 4 of the drawings, a pin 37 extends laterally from the ratchet wheel 29 and has connection with one end of the connecting link 38, the opposite end of the connecting link having connection with the free end of the rod 11 through the pin 39, whereupon movement of the rod 11 produces a relative movement of the ratchet wheel as before stated.

Reference character 40 designates a coiled spring which is supported on the rod 11 and has its upper end contacting with pin 41, the opposite end thereof resting on the brace 19, whereupon movement of the rod 11 in one direction acts to compress the coiled spring, which coiled spring acts to return the rod 11 to its normal position after the rod 11 has been disconnected from the rod 8.

The rod 8 also supports the coiled spring 42 which has its lower end resting on the brace 9, while the upper end thereof engages the pin 43 so that upon movement of the rod 8, spring 42 is placed under tension to return the rod 8 when this rod has been released.

Secured in the lower end of the rod 8 is a transversely extending pin 44 that provides means for connecting the cables 45 and 46, to the rod 8, the cables passing through an opening in the brace 47, from where they pass over the pulleys 48 supported at the lower end of the hollow post 5.

These cables constitute the operating

means employed for imparting movement to the rods 8 and 11 and as shown, these cables pass through tubes 49 which have one of their respective ends positioned in suitable threaded openings in the hollow post 5 at a point adjacent to the base thereof as at 50. The opposite ends of the tubes 49 are disposed in threaded openings of the gear boxes 51.

A shaft 52 has one end thereof positioned in the gear box associated therewith, the opposite end of the shaft being mounted in the bearing 53 disposed adjacent to a railway track, there being provided operating arms 53 on the inner ends of the shafts 52 that extend upwardly from the shafts and lie in the path of travel of a suitable operating arm not shown, and which is carried by the train or car moving over the track.

Each of these operating arms supports an auxiliary section 54 which has pivotal connection with the arm associated therewith at 55, the auxiliary sections 54 being formed with inclined surfaces to contact with the arm carried by the train or car moving over the track to cause the arm 53 to move to a horizontal position, to rotate the shaft 52 associated therewith.

Mounted on the outer end of the arms 53 and connected with the auxiliary sections 54 are the coiled springs 56 that normally hold the auxiliary sections 54 in their initial positions. These springs act to cushion the blow directed to the arm 53, when the operating arm carried by a train or car contacts with the auxiliary section to operate the device.

Disposed on the outer end of each shaft 52 and positioned in the gear boxes 51 are the pulleys 57 to which the cables 45 and 46 are secured, whereupon movement of the pulleys 57 results in a relative movement of the cables. In the operation of the device, assuming that a train is moving in the direction of the arrows as indicated in Figure 1 of the drawings, and the train has passed the road surface, crossing the railway track. Secured to the shaft 7 at a point directly under the cap 6 is a disk 60 to which are secured the springs 61 that have their outer ends secured to the post at a point adjacent to the upper end thereof, so that when the shaft 7 is moved as by a vehicle contacting with the gate 7' when in its closed position, the springs will return the gate to its normal position.

The operating arm carried by the train contacts with the auxiliary section 54 of the operating arm 53 moving the arm in the direction of the arrow to the end that the pulley 57 associated with the actuated arm 53 rotates, exerting a pull on the rod 8, which in turn is moved against the tension of the coiled spring 42. Since the rods 8 and 11 are connected, coiled spring 40 is also

placed under tension. It is obvious that as rod 8 moves downwardly, the pawls 13 contact with the cams 16 which causes the pawls 13 to move outwardly and disengage 5 the shoulders 14 of the rod 8.

During the downward movement of the rods 8 and 11 the ratchet wheel 29 is rotated, which in turn rotates the segmental gear which is in mesh with the mutilated gear 10 30 carried thereby, to the end that the shaft 7 and gate arm 7' supported thereby, is moved to its opened position.

When the pawls 13 release their hold on the rod 8, the spring 40 returns the rod 11 to its normal position, the plunger 28 thereof seating in one of the recesses of the segment 15 25 to lock the shaft 7 and arm against accidental movement. It will be obvious that upon the return movement of the shaft 11, 20 the ratchet wheel 29 moves over the pawls 32. It is to be understood however that the train passing over the track in a direction of the arrow as shown by Figure 1 of the drawings, prior to the operation as described, has contacted with the opposed arm 25 53 to move the gate arm 7' to a position as indicated by Figure 1.

What is claimed as new is:—

1. In a gate operating mechanism, a hollow post, a shaft supported within the post and having its upper end disposed above the post, a gate arm supported on the upper end of the shaft, and means within the post and associated with the shaft for rotating the shaft intermittently in opposite directions.

2. In a gate operating mechanism, a hollow post, a vertical shaft extending above the post, a gate arm supported on the upper end of the shaft and adapted to rotate in a horizontal plane, train controlled means within the hollow post and adapted to operate to rotate the shaft to move the gate arm to its open or closed position, and means for automatically locking the shaft against rotary movement.

3. In a gate operating mechanism, a hollow post, a gate supporting shaft extending into the post, segmental gears mounted on the shaft, a ratchet wheel having a mutilated gear adapted to contact with the segmental gears to rotate the shaft, operating rods within the post, means for connecting the operating rods and ratchet wheel, whereby movement of the rods in one direction causes a rotary movement of the ratchet wheel to rotate the shaft, means for returning the operating rods to their normal positions, means for operating the rods, and means for locking the shaft against movement.

4. In a gate operating mechanism, a hol-

low supporting post, a shaft extending into the post and having one end thereof disposed above the post, a gate arm supported by the shaft and adapted to operate in a horizontal plane, a segment having depressions formed therein, train controlled means supported within the post and adapted to operate to rotate the shaft, and said train controlled means having a spring pressed plunger adapted to move into the depressions to lock the shaft against movement. 65 70

5. In a gate operating mechanism, a hollow supporting post, a movable rod supported within the hollow post and having a bore in one end thereof, a vertically movable rod disposed above the first mentioned rod and having one end thereof disposed in the bore of the first mentioned rod, train controlled means for moving the rods within the supporting post, a gate supporting shaft positioned in the upper end of the hollow post, means for transmitting motion of the rods to the shaft, and means for automatically disconnecting the rods when the rods have moved to the limits of their downward movements. 75 80 85

6. In a gate operating mechanism, a hollow supporting post, a vertical shaft having one end thereof extending above the hollow post, a gate arm mounted on the upper end of the shaft, vertically movable operating rods positioned in the hollow post, coiled spring members for normally urging the rods to their initial positions, means for transmitting movement of the rods to the shaft to rotate the gate arm, train controlled means for actuating the rods, and means for locking the shaft against movement. 90 95 100

7. In a gate operating mechanism, a hollow supporting post, a gate supporting shaft extending into the hollow supporting post, an operating rod having a bore in its upper end, a rod having one end disposed in the bore, means associated with the last mentioned rod and shaft for imparting rotary movement to the shaft when the rods move in one direction, pawls carried by the lower end of one rod, shoulders formed on the opposed rod, said pawls adapted to move into engagement with the shoulders to connect the rod, train controlled means for moving the rods in one direction, and spring members for returning the rods to their initial positions. 105 110 115

In testimony that I claim the foregoing as my own, I have hereto affixed my signature in the presence of two witnesses.

JOE E. COURTNEY.
